DOOR LATCH OPERATING DEVICE

Leland H. Fisler, New Britain, Nicholas A. Welch, West Hartford, and Frank J. McConnell, New Britain, Conn., assignors to The American Hardware Corporation, New Britain, Conn., a corporation of Connecticut

Application January 31, 1952, Serial No. 269,168

12 Claims. (Cl. 292—1)

This invention relates to a door latch operating device and more particularly to a latch operating unit of the cylindrical type.

The invention is embodied in a latch operating unit of the cylindrical type which is insertable into an opening extending transversely through a door for operating a latch unit which is disposed in a hole in the edge of the door that extends perpendicularly to the axis of the said opening.

Conventional door latch operating units of the cylindrical type commonly comprise a basic unit in which the components forming the inner and outer portions of the unit differ in construction. In order to provide such units with different operating characteristics, or locking functions, it is necessary to disassemble the basic unit, remove some of the parts and substitute different parts for the elements removed. Since each function requires parts that are different from the parts required in other functions, and the parts of the conventional basic units vary in form on the inner and outer sides of the units, it has been necessary for the manufacturer to produce and maintain a large supply of parts which can be assembled into the basic unit in order to provide the locking function called for. This procedure renders the lock expensive to manufacture and difficult to produce. In addition, when it is desired to change the function of a lock after it has been installed upon a door, it becomes necessary to obtain many new parts or to purchase an entire new lock since it is often found that the parts of the original lock can not be used with the parts required for the new function.

An object of this invention, therefore, is to provide a door latch operating unit of the cylindrical type comprising a basic unit which is constructed of parts that are identical on both the inner and outer sides of the unit.

A further object of this invention is the provision of a basic operating unit whose construction remains the same for all functions of the unit to thereby eliminate the necessity of disassembling or changing the construction of the basic unit to provide the various functions.

A still further object of the invention is the provision of a basic operating unit into which parts may be inserted to change its function without disassembling the entire unit.

A still further object of this invention is to provide a cylindrical latch operating unit which is rendered inexpensive to manufacture by having the majority of parts for the various functions identical and thereby eliminating the necessity of manufacturing or maintaining a large parts inventory.

Further objects and advantages of this invention will be more clearly understood from the following description and the accompanying drawings in which:

Fig. 1 is a plan view of the basic latch operating unit with parts thereof in central horizontal section.

Fig. 2 is a similar view, but with additional parts in section, to more clearly illustrate the construction of the unit.

Fig. 3 is a sectional end view on line 3—3 of Fig. 1.

2

Fig. 4 is a fragmentary sectional view, on line 4—4 of Fig. 3, further illustrating the construction of the operating unit.

Fig. 5 is a side view, partially in central vertical section on line 5—5 of Fig. 2.

Fig. 6 is a sectional end view of a portion of the latch operating unit on line 6—6 of Fig. 5.

Fig. 7 is a similar view on line 7—7 of Fig. 5.

Fig. 8 is an end view, partially in section, illustrating the construction of the knob retainer employed in our improved operating unit.

Fig. 9 is a similar view illustrating the knob retainer in depressed position.

Fig. 10 is an end view of a portion of our improved operating unit taken on line 10—10 of Fig. 1 and illustrating the construction of the casing thereof.

Fig. 11 is an exploded perspective view illustrating some of the parts of our improved latch operating unit and the relative positions which they occupy.

Fig. 12 is a fragmentary view of a portion of the latch construction shown in Fig. 2, illustrating a modification adapting the latch as an exit door structure.

Our improved door latch operating unit includes a casing, generally indicated at 5, which houses and supports the latch operating mechanism and consists of an assembly of parts including an inner end plate 6 and an outer end plate 7 having integral sleeves 8 and 9 extending therefrom respectively. The end portion of each of said sleeves 8 and 9 is of a reduced diameter and it will be noted that the end plates 6 and 7 and their respective sleeves 8 and 9 are identical in form with the exception of a portion of the sleeve 9 which is provided with a screw thread 10.

Each of the end plates 6 and 7 is provided with oppositely disposed pairs of horizontal slots 11 for the reception of ears 12 and 12-a which project from the inner and the outer sides, respectively, of a retractor guide 13 which is in the form of a U-shaped member that is received between the plates 6 and 7. The forward edge 40 of each of the ears 12 and 12-a is provided with a notch 14 which receives the forward edge 11-a of the corresponding slot 11, upon rearward transverse movement of the end plates relatively to the retractor guide, to thereby secure said end plates to the guide in coaxial position and against axial movement relatively thereto.

The retractor guide 13 is provided with a pair of longitudinally extending grooves 15—15 in the inner surface of each of its leg portions 13-a and 13-b for the reception of ball members 16 which support a retractor 17 in the retractor guide 13.

The retractor 17 is formed of a single piece of sheet metal and includes an inner side portion 18 from which is bent an upper leg 19 and a lower leg 20. The rear portion of each of said legs 19 and 20 has an extension 21 and 22, respectively, which is bent inwardly to form the outer side of the retractor. The inner side 18 of the retractor is also provided with extensions which are bent inwardly and extend across the retractor to provide rollback platforms 23—23 on said retractor. The portions forming the outer side, the rollback engaging portions and a portion of the inner side of the retractor are spaced apart to provide a slot 24 therein to accommodate additional parts which are insertable into the basic unit to provide different operating characteristics. The outer ends of the retractor legs 19 and 20 extend inwardly to provide fingers 25 and 26 which engage a retractor bar extending from a conventional latch unit, not shown, to transmit movement of the retractor to the latch bolt in said unit.

The outer surfaces of the legs 19 and 20 of the retractor are grooved, as at 27, for the reception of the balls 16 which provide anti-friction bearings for the re-

tractor to facilitate its movement in the retractor guide 13. The balls 16 are maintained in proper relative position by cages 28-28 which are located between the legs of the retractor guide 13 and the legs of the retractor 17 as clearly illustrated in Figs. 3 and 5. The legs 13-a and 13-b of the retractor guide are properly spaced by the ears 12 and 12-a as they are inserted into the slots 11 in the end plates 6 and 7 during assembly of the unit to thereby provide the proper clearance for the balls 16.

The inner end of the retractor guide 13 has secured thereto a spring support 29 from which projects a pair of fingers 30-30 that support the rear ends of compression springs 32-32. The free ends of the spring 32 project into the retractor 17 and engage ears 33-33 which extend from the opposite sides 34-34 of a U-shaped guide member 35 and are supported by the rollback engaging portions 23-23 of the retractor. The sides 34-34 of the guide member 35 are spaced apart a distance substantially equal to the width of the slot 24 and extend between the springs to provide guide means for the various dogging bars that are insertable into the unit. It will be understood that the guide member 35 is retained in the retractor by the springs 32-32 and said springs urge the retractor outwardly with respect to the casing.

The inner sleeve 8 and the outer sleeve 9 are each provided with identically formed bearing members 36-36 which fit within the sleeves, as illustrated in Fig. 2, and are prevented from rotating relatively thereto by means of tabs 37 which are bent inwardly from each of said sleeves and project into a slot 38 extending the length of each of said bearings. Movement of each of said bearings 36 longitudinal of its respective sleeve is prevented by means of a finger 39 which is bent inwardly from each of said sleeves into a notch 40 formed in the rear edge of each of said bearings.

The bearing 36 in each of said sleeves 8 and 9 rotatably supports a tubular spindle member 41 which provides an inner and an outer actuator for the retractor. Each of the spindles 41-41 is identical in form and has a segmental portion 42 projecting therefrom into the casing 5. The opposite edges of said portions 42 are bent outwardly to provide rollback portions 43-43 which engage the platforms 23-23 of the retractor to both limit the outward movement of the retractor under the force of the springs 32 and cause retraction thereof when either of the spindles is rotated. The outer ends of the spindles contain notches 41-a and 41-b for the reception of other mechanism which is insertable into said spindles to provide the various locking functions required.

Each of the spindles 41-41 carries a thrust washer 44 which, as fully disclosed in the copending application of Frank J. McConnell, Serial No. 275,618, filed March 8, 1952, is in the form of an annular ring having an opening 44-a therethrough into which the spindle projects. The opening 44-a has radial lugs 45-45 which enter notches 46-46 in the end of the spindle and extend behind the rollback portions 43-43 to thereby prevent axial movement of the spindle relatively to the thrust washer. As illustrated in Figs. 2 and 5 it will be noted that the thrust washers lie between the sides of the legs of the retractor guide and the inner surface of the end plates to thereby permit rotation of the washer with its spindle, but prevent axial movement thereof. In order to provide the proper clearance between the sides of the retractor guide and the end plates to prevent binding of the thrust washers, the said retractor guide has lateral extensions 13-c and 13-d thereon which engage said end plates. Each of said spindles carries a knob 47 having a shank 48 extending therefrom which receives the spindle and enters the reduced portion of the sleeves 8 and 9 to provide a bearing for the outer end of the spindles as illustrated in Fig. 2. Each of the knobs is identically constructed and the shank portions thereof have a projection 49 which extends into a slot 50 running the length of

the spindle to thereby prevent rotation of the knob relatively to the spindle.

In order to prevent removal of the knob from its spindle we have provided a novel knob retainer of the type fully described in the copending application of Leland H. Fisler, Serial No. 303,529, filed August 9, 1952, which is in the form of a semicircular catch 51 which is positioned in the interior of the spindle and has a tongue 52 projecting therefrom through a slot 53 in the spindle into a slot 54 in the knob shank as illustrated in Fig. 8.

The catch 51 has a lateral extension 55 on one end thereof which projects into a slot 56 in the spindle to thereby provide a guide for the catch. The other end of the catch lies against an ear 57 which is bent inwardly from the spindle and pivotally supports the catch to permit movement from its retaining position, illustrated in Fig. 8, to its depressed position illustrated in Fig. 9. The catch is urged into locking position by means of a spring 58 which extends longitudinal of the spindle and is supported therein by bridging members 59-59 formed in the spindle. The spring is retained in position by bending a portion of it downwardly between the bridging members as illustrated at 60. A guard 61 is bent inwardly to prevent interference of the spring with parts of the locking mechanism which are insertable into the spindle.

In order to assemble the parts of our novel operating unit, the guide member 35 is first inserted into the retractor and the springs 32-32 are then placed on the fingers 30-30 of the spring support 29. The retractor 17 is inserted into the retractor guide 13 with the balls 16 and the cages 28 in proper position. The thrust washers 44 are then placed upon the spindles 41 by passing them over the end of the spindle until the lugs 45-45 are located behind the rollback portions 43-43 and in the notches 46-46. The spindle is compressed slightly and the washer is then passed onto the end of the spindle. The inherent resiliency of the spindle will retain the washer in position thereon and yet allow a small degree of movement of the washer relatively thereto to permit proper alignment of the parts as they are assembled into the operating unit.

The spindles are inserted into their respective sleeves and through the bearing member 36. Interference from the tongue 52 on the knob catch 51 is avoided by depressing the catch to permit it to pass through the bearing 36 whereupon the spring 58 will project it to its normal position. The end plates 6 and 7 are then placed upon the ears 12 and 12-a respectively of the retractor guide and when located against the sides of the guide they are moved rearwardly relatively to the guide so as to bring the edges 11-a of the slots 11 into the notches 14 thereby locating the entire assembly in the proper position with the rollback portions 43-43 in engagement with the portions 23-23 of the retractor. When the end plates are thus assembled to the retractor guide, the rearward portion of the guide, which joins the legs thereof, and the forward free ends of said legs are substantially flush with the peripheral edges of said end plates as clearly illustrated in Fig. 3.

The retractor 17 is then depressed against the springs 32-32 and a cup-shaped cover 62 is passed over the entire assembly to the position illustrated in Fig. 1 wherein the tabs 63 projecting from the cover are bent downwardly over the outer end plate 7 to thereby permanently secure the cover in assembled position. It will be seen from Fig. 3 that the annular wall of the cover 62 fits closely around the assembled end plates and retractor guide and prevents relative transverse movement thereof and disengagement of the connecting means therefor. The surface of the cover 62 contains an opening 64 through which the fingers 25 and 26 of the retractor normally project so as to permit engagement of said fingers with the retractor bar in the latch unit which is guided into position relatively to the latch operating unit by the edges 65-65 of the opening 64 in the conventional manner. The end wall

66 of the cover 63 contains a rectangular opening 67 to provide a clearance for the inner sleeve 8.

The latch operating unit is properly located in the hole extending through the face of the door by means of outer and inner circular clamping plates 68 and 69 respectively.

The outer clamping plate 68 has a threaded sleeve 68-a projecting perpendicularly therefrom which is threaded to the sleeve 9 to permit axial adjustment of the clamping plate relatively to the casing 5 to adapt the unit to doors of different thicknesses. The outer clamping plate also has a pair of spurs 70—70 projecting therefrom which pierce the door and prevent rotation of said plate by persons attempting to remove the unit from the outer side of the door. A decorative rose 71 is permanently secured to the clamping plate and projects outwardly therefrom over the sleeve 9.

Before the latch operating unit is inserted into the hole in the door and into engagement with the conventional latch unit projecting into said hole from the edge of the door, the outer clamping plate is placed over the end of the outer spindle 41, but is not threaded onto the sleeve 9. The shank 48 of the outer knob 47 is then placed over the outer spindle with the projection 49 thereon in alignment with the slot 50 in the spindle. The knob is pressed onto the spindle until the end of the shank engages the tongue 52 of the knob catch 51 which projects through the spindle. The said tongue, which is accessible through a slot 72 in the sleeve 9, is then depressed with a suitable tool, as illustrated in Fig. 9, and the knob shank is urged inwardly on the spindle until the slot 54 in said shank is in alignment with said tongue whereupon the spring 58 will project the tongue outwardly through said slot 54 and lock the knob to the spindle.

The clamping plate 68 is then threaded onto the portion 10 of the sleeve 9 and properly adjusted thereon in accordance with the thickness of the door. The entire unit is then inserted into the hole in the door and moved therethrough until the clamping plate 68 abuts the outer surface of the door.

The inner clamping plate 69 has an annular raised portion 73 which projects into the hole in the door and prevents movement thereof relatively to the door. The said plate is further provided with oppositely disposed pairs of openings 74 which receive the ears 12 projecting from the retractor guide to permit immediate alignment of the holes 75—75 in said plate with threaded holes 76—76 in the end plate 6. An opening 77 is formed in said clamping plate 69 to receive the sleeve 8 and said opening is bounded by outwardly extending arms 78 which are bent from said plate and engage the sleeve 8 to support the inner end of the operating unit.

The inner clamping plate is provided with a detachable rose 79 which is secured to the plate in the conventional manner.

After the operating unit is in proper position in the door, the inner clamping plate is passed over the end of the inner spindle and the sleeve 8 and rotated until the openings 74 are in alignment with the ears 12 extending from the retractor guide. The clamping plate is then moved onto said ears and screws 80—80 are inserted through the holes 75—75 therein and threaded into the holes 76—76 in the end plate 6. The screws 80—80 are tightened thereby drawing the outer and inner clamping plates securely against the door to properly position the lock therein.

The inner rose is passed over the end of the inner spindle and the inner knob is applied thereto in the same manner as the outer knob; access to the inner knob catch 51 being had through the slot 72 in the sleeve 8. The inner rose 79 is then secured to the clamping plate 69 and the installation is complete.

It will be noted that the inner rose 79 and the outer rose 71 project outwardly from their respective clamping plates and over the sleeves 8 and 9 to thereby cover the slots 72—72 in said sleeves and prevents access to the

knob catches 51. This is of particular importance on the outer side of the lock, where the rose 71 is permanently secured to the clamping plate, since it prevents removal of the outer knob by unauthorized persons attempting to force entry into a house when our improved operating unit is used as a door lock.

It will also be understood that by securing the end plates to the retractor guide through the engagement of the ears 12 and 12-a with said end plates, the operating unit is rendered extremely strong since all of the end thrust applied to the knobs is carried by the retractor guide and not the cover 62 thereby making it possible to reduce the thickness of the material forming the cover and consequently provide a saving in the cost of manufacture.

It will be understood from the above description that our improved latch operating unit is constructed of parts which are identically formed thereby reducing the cost of manufacturing the unit. Furthermore, by simply removing the knobs from the spindles and inserting various parts into the spindles the operating characteristics of the basic unit may be changed to provide many different lock functions according to the use to which the lock is put.

It will be understood that the mechanism disclosed herein is adapted for use in doors which do not require a lock since rotation of either of the knobs will rotate its respective spindle and through engagement of the rollback portions on the spindle with the portions 23 or 24 of the retractor will cause retraction of said retractor to withdraw the bolt and permit opening of the door.

By merely bending the tab 37 in the outer sleeve 9 downwardly into the slot 50 in the outer spindle, as illustrated in Fig. 12, the basic passage unit may be transformed into a lock for an exit door since the sides of the slot in said spindle will provide abutments which engage the tab to prevent said spindle from turning and it is, therefore, inoperative to retract the retractor while the inner spindle remains operative at all times.

In addition to providing a cover for the knob catch 51 to secure said catch against release, the outer rose 71 also prevents access to the tab 37, when the unit is installed upon a door.

We claim:

1. In a door latch operating device, an assembly comprising a separate substantially U-shaped member including an upper and a lower leg and a portion connecting said legs, an inner and an outer end plate disposed against the opposite sides of said member, cooperative means on said end plates and said member for locating said end plates co-axially with respect to each other, an outer casing closely fitting around said assembled end plates and member, and means on said casing engaging said end plates and holding said end plates and member in assembled relationship.

2. In a door latch operating device, an assembly comprising a separate substantially U-shaped retractor guide including an upper and a lower leg and a rearwardly disposed portion connecting said legs, an inner and an outer end plate disposed against the opposite sides of said retractor guide, means detachably connecting said end plates to the opposite sides of said guide and holding them against axial movement relatively thereto, and a cover member positioned over and closely fitting around said assembled end plates and guide and holding said plates and guide against disengaging movement which would cause separation of said connecting means.

3. In a door latch operating device, an assembly comprising a separate substantially U-shaped retractor guide, ears extending from the opposite sides of each of the retractor guide legs, an inner and an outer end plate disposed against the opposite sides of said retractor guide and having slots therethrough to receive said ears whereby said end plates are positioned co-axially with respect to each other against the sides of said guide, an outer casing closely fitting around said assembled re-

tractor guide and end plates, and means on said casing engaging said end plates and holding said retractor guide and end plates in assembled relationship.

4. In a door latch operating device, an assembly comprising a separate substantially U-shaped retractor guide, ears extending from the opposite sides of each of the retractor guide legs, an inner and an outer end plate disposed against the opposite sides of said retractor guide and having slots therethrough to receive said ears, means detachably connecting said end plates to said ears, and an outer casing closely fitting around said assembled retractor guide and end plates, the walls of said casing holding said retractor guide and end plates in assembled relationship.

5. In a door latch operating device, a casing comprising a separate substantially U-shaped retractor guide including upper and lower forwardly extending legs and a rearwardly disposed portion connecting said legs, an inner and an outer end plate disposed against the opposite sides of said guide, interengageable connecting means for said end plates and said retractor guide engageable by relative transverse movement between said guide and end plates for securing the end plates to the opposite sides of the guide, and a cover member positioned over said assembled end plates and guide, and holding said plates and guide against disengaging movement which would cause separation of said connecting means.

6. In a door latch operating device, a casing comprising a separate substantially U-shaped retractor guide, including upper and lower forwardly extending leg portions and a rearwardly disposed portion connecting said leg portions, an inner and an outer end plate at the opposite sides of said guide, interengageable connecting means for said end plates and said retractor guide engageable by relative transverse movement between said guide and end plates for securing the end plates to the opposite sides of the guide, the opposite ends of said retractor guide, when in assembled and connected position, being substantially flush with the adjacent edges of said end plates, and a cover member positioned over said assembled end plates and guide to prevent transverse disengaging movement thereof and disengagement of the end plates from the opposite sides of the retractor guide.

7. In a door latch operating device, a casing comprising a separate U-shaped guide having ears extending from the opposite sides of the upper and lower legs thereof, an inner and an outer end plate disposed against the opposite sides of said refractor guide and having slots therein through which said ears extend; the corresponding edges of said ears each being provided with a notch which is disposed in alignment with its respective end plate and is adapted to receive the edge of the respective slot therein upon lateral movement of said end plate relatively to the guide to secure said end plates against axial movement relatively thereto, and means normally retaining said end plates and guide in engagement.

8. In a door latch operating device, a casing comprising a separate substantially U-shaped retractor guide having an upper and a lower forwardly extending leg and a rearwardly disposed connecting portion, a plurality 60

of ears extending from the opposite sides of said legs, an inner and an outer end plate disposed against the opposite sides of said guide and having slots therein through which said ears extend; the corresponding edges of said ears each having a notch therein disposed in alignment with its respective end plate and adapted to receive the edge of the respective slot in said end plate upon lateral movement of said end plate relatively to said guide to retain said end plates against axial movement relatively thereto; the opposite ends of said retractor guide being substantially flush with the adjacent edges of said end plates, a cover member extending over said end plates and normally engaging the opposite ends of said guide to prevent relative lateral movement thereof and disengagement of said end plates from said notches, and means on said cover member retaining it in position.

9. The subject matter set forth in claim 8, wherein the slots in said end plates are spaced apart a predetermined distance to properly space the upper and the lower legs of the retractor guide when said ears are inserted thereinto.

10. In a door latch operating device of the kind normally including a casing having retracting means therein, and an inner and an outer spindle rotatably carried by said casing for operating said door latch, an abutment means on said outer spindle; a bendable spindle locking means carried by said casing adjacent to and in alignment with said abutment means when the outer spindle is in normal relaxed position, said locking means being bendable into engagement with said abutment means to prevent rotation of the outer spindle and thereby convert said device to an exit door latch operating device.

11. In a door latch operating device of the kind normally including a casing having retracting means therein, and an inner and an outer spindle rotatably carried by said casing for operating said door latch, an inner and outer end plate, an inner and outer sleeve extending from each of said end plates respectively, said inner and outer spindles being journaled for rotation in a corresponding sleeve, a slot in the outer spindle; a bendable spindle locking means on the outer sleeve, said locking means being adjacent said slot and bendable into engagement therewith to prevent rotation of the outer spindle and thereby convert said device to an exit door latch operating device.

12. A door latch operating device as set forth in claim 11, wherein said spindle locking means is in the form of a tab that is formed integrally with the outer sleeve.
